DESIGN FOR A SHOE

Alfred Ornsteen, Brookline, Mass., assignor to Tober-Saifer Shoe Company, St. Louis, Mo., a corporation of Missouri

Application June 4, 1938, Serial No. 77,574

Term of patent 3½ years

To all whom it may concern:

Be it known that I, Alfred Ornsteen, a citizen of the United States, residing at the city of Brookline, in the county of Norfolk and State of Massachusetts, have invented a new, original, and ornamental Design for a Shoe, of which the following is a specification, reference being had to the accompanying drawing forming a part thereof, in which

Fig. 1 is a perspective view; Fig. 2 is a plan view, and Fig. 3 is a side view of a shoe showing my new design.

I claim:

The ornamental design for a shoe, substantially as shown.

ALFRED ORNSTEEN.
